FREDERICK A. WISWELL, OF OAKLAND, CALIFORNIA, ASSIGNOR OF TWO-FIFTHS TO
ELIZABETH E. PHELAN, OF OAKLAND, CALIFORNIA.

ORE GRINDING OR PULVERIZING MACHINE.

1,207,687.

Specification of Letters Patent.

Patented Dec. 5, 1916.

Application filed July 29, 1915, Serial No. 42,580. Renewed April 29, 1916. Serial No. 94,483.

To all whom it may concern:

Be it known that I, FREDERICK A. WISWELL, a citizen of the United States, residing at Oakland, in the county of Alameda and State of California, have invented certain new and useful Improvements in Ore Grinding or Pulverizing Machines, of which the following is a specification.

The present invention relates to improvements in machines for grinding or pulverizing ores or the like containing precious metals, for their recovery, while not necessarily restricted to such use.

An important object of the invention is to provide a machine of the above mentioned character, so constructed that the grinding or pulverizing of the ore containing the precious metal, and the amalgamating of the metal, may be simultaneously performed.

A further object of the invention is to provide a machine of the above mentioned character, the elements of which are arranged in a highly compact and convenient manner.

Other objects and advantages of the invention will be apparent during the course of the following description.

In the accompanying drawings forming a part of this specification and in which like numerals are employed to designate like parts throughout the same, Figure 1 is an end elevation of the apparatus, Fig. 2 is a transverse sectional view taken on line 2-2 of Fig. 3, and, Fig. 3 is a vertical longitudinal sectional view taken on line 3-3 of Fig. 1.

In the drawings, wherein for the purpose of illustration is shown a preferred embodiment of my invention, the numeral 10 designates preferably horizontally arranged rails or castings, constituting the foundation of the machine. These rails or castings are connected at their ends, by preferably diagonally arranged braces 10', as shown. Disposed between these rails or castings is a horizontal trough 11, having its upper end open to receive the lower portion of a revolving drum, to be described. This trough receives the pulp and water from the drum. Journaled within these bearings are transverse shafts 17 and 18, having flanged supporting rolls 19 and 20, rigidly mounted thereon, respectively. The shaft 17 extends at one end outwardly beyond its bearing for a substantial distance, and has a pulley 21

rigidly mounted thereon, which is adapted to receive rotation from a belt or the like. A pinion or gear 21' is also rigidly mounted upon this shaft.

The numeral 22 designates a cylindrical casing or drum as a whole, which is rotatably supported by the rolls 19 and 20, in a manner to be described. This drum, as more clearly shown in Figs. 1 and 2, comprises an outer annular casing or ring 23, upon one end of which is formed an annular gear 24, having an annular groove 25, disposed upon its inner side. This annular gear 24 meshes with the gear 21', as shown. The gear 24 carries an inwardly extending annular overflow flange 26, and a corresponding annular overflow flange 27 is arranged upon the opposite side of the outer casing 23, and secured thereto by means of bolts 28 or the like. Disposed within the outer casing 23 is an inner protecting casing or lining 29, formed of hard steel or the like and held in place between shoulders 30, as shown. This protecting lining is rigidly secured to the outer casing 23 for rotation therewith. As clearly shown in Fig. 3, the outer casing 23 contacts with the supporting rolls 19 and 20, and is supported thereby, while the flanges of these rolls operate within the annular groove 25 and adjacent the opposite end of the casing 23, to prevent improper lateral movements of the casing.

As shown in Fig. 3, each of the annular overflow flanges 26 and 27 carries a section of foraminous material 36.

Arranged within the drum 22, is a pulverizing or grinding roll 40 of suitable diameter to pass through either of the rings 31. This grinding roll has its periphery protected by a hard steel annular casing or covering 41, as shown. The casing 41 is adapted to contact with the ore or the like fed between it and the inner lining 29 of the outer drum. The roll 40 is carried by a transverse shaft 42, extending through openings 43, formed in vertically movable bearings on slides 44. These openings 43 have their lower ends open, as shown. The bearings or slides 44 are vertically movably mounted within vertical guides 45, preferably formed integral with the horizontal bars 12. Rigidly attached to the upper ends of the vertical guides 45 are transverse horizontal heads 46, having screw-threaded openings to receive vertical adjusting screws 47, the lower ends 110

of which have swiveled connection with the bearings or slides 44. These adjusting screws 47 are turned by hand wheels 48, rigidly attached to their upper ends, as shown. The bearings 44 are normally spaced a slight distance above the shaft 42, the weight of the grinding roll 40 being normally sufficient to crush or pulverize the ore. When the weight of this roll is not sufficient for this purpose, its crushing action may be increased by turning the hand wheels 48 in the proper direction, which turn the adjusting screws and through the medium of the bearings 44 force the roll 40 to a lower position in contact with the ore.

The numeral 50 designates horizontal rails which are bolted or rigidly secured to the heads 46. Secured to corresponding ends of the rails 50, are upstanding rods 51, to the upper ends of which are attached a hopper 52, for receiving suitably treated ore containing precious metal. Attached to the lower end of the hopper 52 is a spout 53, the lower end of which is arranged to discharge the material between the contacting faces of the inner roll and drum, as more clearly shown in Fig. 3.

The numeral 54 designates a water supply pipe, discharging the water upon the opposite side of the roll, as shown.

The operation of the apparatus is as follows: The drum 22 is preferably driven clockwise, as indicated by the arrow in Fig. 3, such rotation being imparted thereto from the gear 21'. The ore containing the precious metal after suitable treatment, is fed into the hopper 52, and gravitates therefrom, in suitable amounts, through the spout 53, to be fed between the contacting faces of the grinding or crushing roll and drum. Simultaneously with this supply of ore, a suitable amount of water is fed through the pipe 54, to the opposite side of the roll. The pulp and water rise above the overflow flanges or members 26 and 27, and pass through the foraminous sections 36 into the trough 12. The large particles of the ore which have not been properly ground or pulverized, cannot pass through this foraminous material and are retained within the drum, until properly ground or pulverized. The small particles of precious metal, such as gold or the like, gravitate to the lower portion of the drum and are retained therein by the overflow flanges or members. Should

any of these fine particles of precious metal, pass with the pulp and water to the trough 11, they will settle therein and may be subsequently removed and collected. If desired, mercury may be fed into the drum 6 during the pulverizing operation, whereby the amalgamating process will be practised substantially simultaneously with the pulverizing of the ore. The mercury having a high specific gravity will be retained within the drum by the overflow flanges. The mercury and amalgamated precious metals may be removed from the drum by any suitable means, such as opening one of the doors 35 and removing the same by a suitable receptacle. If desired, one of the overflow flanges may be provided with an opening normally covered by a valve or the like, not shown.

It is to be understood that the form of my invention herewith shown and described is to be taken as a preferred example of the same, and that various changes in the shape, size, and arrangement of parts may be resorted to without departing from the spirit of the invention or the scope of the subjoined claim.

Having thus described the invention, I claim:

In a machine of the character described; a supporting structure; supporting rolls carried thereby; a drum arranged above and contacting with the supporting rolls, said drum comprising an annular outer casing having an annular gear formed upon one end thereof and an inner annular overflow flange formed upon the annular gear, said annular casing being provided near the annular gear with an interior shoulder; a second annular overflow flange connected with the opposite end of the annular casing and arranged interiorly thereof to form with the first named flange an annular recess; an annular protecting lining arranged within the annular recess and contacting with the shoulders of the recess; a grinding roll arranged within the drum to coöperate with the annular protecting lining; and means to drive the drum, embodying a gear engaging the annular gear.

FREDERICK A. WISWELL.
